(57) **CLAIM**

The ornamental design for a steamer for clothing, as shown and described.

DESCRIPTION

FIG. 1 is an upper perspective view of the steamer for clothing showing my design.

FIG. 2 is a side elevation view thereof;

FIG. 3 is an opposite side elevation view thereof;

FIG. 4 is a front elevation view thereof;

FIG. 5 is a back elevation view thereof;

FIG. 6 is a top plan view thereof;

FIG. 7 is a bottom plan view thereof; and,

FIG. 8 is a bottom perspective view thereof.

The steamer for clothing is a hand-held appliance for applying steam to an article of clothing.
